UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,035, dated July 3, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts hereinafter more fully pointed out.

A, B, and C are three bouquets or clusters of flowers, which are placed on the background of the carpet so as to leave a triangular space

in the arrangement shown, although when the 15 carpet is matched the group A will also be horizontally between the groups B and C, as indicated in the lower part of the photograph. The space between these bouquets is filled with a cluster of small flowers, a. 20

I claim—

The design for carpets, consisting of the groups A, B, C, and a, substantially as shown.

PAUL PIGNOT.
